BAG AND METHOD OF MAKING SAME

Robert N. Cundall, Hamburg, and William B. Powell, Buffalo, N. Y., assignors, by means assignments, to Bagpak, Inc., a corporation of Delaware

Application January 10, 1931, Serial No. 507,874

18 Claims. (Cl. 229—62)

This invention relates to a bag and method of sealing the same and more particularly to multiple walled bag adapted to contain powdered materials, such as flour, sugar, lime, plaster, gypsum, 5 fertilizers and the like, in which it is not only necessary to close the bag in such manner that the fastenings at the mouth of the bag will not break or loosen but also to provide a seal which prevents the leakage or sifting out of the contents 10 when the bags are handled either when the bags are inverted or when they are set down and the material tends to blow out through the impact of setting the bag down.

In the development of open mouth paper bags 15 for use as larger sized packages of powdered materials it has been found desirable to make them with the walls of a number of thicknesses of paper. As there is a limit to the strength which can be obtained from a single thickness of paper the most 20 effective way to provide the necessary strength for large bags has been found to provide a bag having a number of walls or in effect a single bag made of a number of bags set one within the other. This not only provides the requisite strength but 25 also permits of employing a moisture-resistant bag or wall as the outer wall which can be thin and inexpensive and not only protects the contents of the bag but also protects the inner walls or bags which can be made of a non-moisture re- 30 sistant paper. While this development has produced bags of sufficient strength, their use has been prevented from a more general application, particularly in the handling of fine, dusty materials because of the difficulty in making them 35 sift-proof at the mouth when the closure was made, and in the case of the larger sizes of bags the need of extra strength at the mouth or place of closure.

This specification is a companion to the applications of Robert N. Cundall, Serial No. 507,615, 40 filed January 9, 1931, and Serial No. 507,616, filed January 9, 1931.

One of the principal objects of this invention 45 is to provide a bag for finely powdered or dusty materials in which the mouth of the bag is closed in such manner as to provide a strong, durable and permanent closure and seal which is also sift-proof and entirely prevents the fine, dusty materials from sifting out through the closure. 50 Another purpose is to provide a bag which when closed is as strong at the mouth or place of sealing as any other portion of the bag.

Another aim is to provide a bag of this character 55 in which there is no danger of the sealing material falling into the contents of the bag.

A further object is to provide such a bag and process which permits of the sealing of the bag to be provided by automatic processes and avoid all hand operations.

A still further aim is to provide a bag which is 5 neat in appearance and can be provided with a sift-proof seal of the requisite strength at very low cost.

Another purpose is to provide a bag which is 10 effectively sealed against the possibility of contamination, thereby enabling it to be used for the transportation of foodstuff and which is also pilferproof thereby enabling it to be used for transporting goods which are relatively valuable 15 and subject to pilfering.

In the accompanying drawing:

Fig. 1 is a fragmentary perspective view of a bag made in accordance with our invention.

Fig. 2 is a fragmentary end elevation thereof.

Fig. 3 is a fragmentary vertical section through 20 the form of bag shown in Fig. 1.

Fig. 4 is a fragmentary top plan view of the form of the invention shown in Fig. 1 showing the same preparatory to sealing.

Fig. 5 is a fragmentary vertical section through 25 a modified form of the invention.

Fig. 6 is a fragmentary perspective view of a still further modified form of the invention.

Fig. 7 is a vertical section through the modified 30 form of the invention shown in Fig. 6.

Fig. 8 is a vertical section showing another modification of the present invention.

Fig. 9 is a perspective view showing a still 35 further modification of the present invention.

Fig. 10 is a vertical section through the form 35 of the invention shown in Fig. 9.

In the present application the invention is shown as embodied in a bag which is already formed, i. e. in closing and sealing the mouth of a fabricated bag, but it will also be apparent that 40 the invention can be embodied in closing and sealing the bottoms of bags during their manufacture.

One of the most effective ways of closing a 45 multiple walled bag containing dusty materials is by stitching the sides of the mouth of the bag together with cotton thread. Stitching through the sides of the mouth of the bag, however, has the effect of weakening the bag and dusty materials will leak through the top of the bag between the stitches. Also in the stitching of the bag the stitching needle is, of course, larger than the cotton thread used in stitching and therefore the needle punches a larger hole through the 50 walls of the bag than the thread fills and these 55

large holes permit the dusty material to escape through the holes in the bag around the thread.

The most effective way that has been found to make a bag tight or sealed at the opening is by some form of gluing. Inasmuch, however, as the principal object of employing a multiple walled bag is to obtain the required strength it is obvious that in cases where great strength is needed unless some method of reinforcing this seal is obtained, it will not be as strong as the walls of the bag. The present invention therefore proposes to combine stitching and gluing in such manner that the stitching provides a closure of the necessary strength and the gluing not only seals the bag at the closure but also strengthens the stitching. While the invention proposes the use of stitching and gluing it will be apparent that in place of the stitching another form of fastening which extends through the walls of the bag could be employed, such as staples, and that while glue is preferable any adhesive or plastic hardening material can be employed, preferably one that is quite liquid at the time of application and will harden to a stiff gummy condition, such a condition being preferable to a glue which becomes brittle.

The invention is shown as embodied in a multiple walled bag having an inner wall 10 and an outer wall 11, such a multiple walled bag being in effect one bag within the other, although the invention can be embodied in a bag having any number of walls. Such a multiple walled bag is made in any suitable manner to provide a mouth 12 at its upper end which when furnished to the packer can be opened up and the materials deposited in the bag.

In the form of the invention shown in Figs. 1-4, when the bag is furnished to the packer one of the sides of the outer wall 11 of the bag is extended upwardly to form a flap 13, this flap being substantially equal in length to half the circumference of the mouth of the bag and extending from one end of the mouth to the other. The bag so furnished also has a slit 14 provided at each end of the mouth 12 in the outer shell or wall 11 and extending downwardly from the mouth of the bag.

The bag is furnished to the packer in a collapsed or flattened condition, the packer opens up the mouth of the bag and deposits the dusty or powdered materials through the mouth 12 into the bag. He then runs the mouth of the filled bag through a sewing machine and closes the mouth of the bag by a row of stitches 15. In so sewing the bag the packer folds back the wing or extension 13 so that it is disposed horizontally as shown by the dotted lines in Fig. 2 and the stitches are passed through the remaining upstanding walls of the bag at the mouth. In other words, as best indicated in Fig. 3, the stitching passes through both sides of the inner wall or shell 10 of the bag and one side of the outer wall or shell 11 of the bag. This stitching is started at one end of the mouth and is carried beyond the opposite end so that when the bag is sewed in this manner a secure and tight closure is provided for the mouth of the bag.

In the absence of provision to prevent it, however, the dusty or powdered materials contained in the bag would leak out through the mouth of the bag past the stitching 15. Also since the needle of the sewing machine must necessarily be larger than the thread 15 the holes 18 formed by the needle are of greater size than the thread 15

and some leakage is liable to occur through these holes 18, particularly when the bag is set down with some force. To prevent this the present invention proposes a seal of glue or some other hardening plastic adhesive. With the form of the invention shown in Figs. 1-4 this glue 17 is applied to the whole of the inner face of the flap or wing 13 extending down to the bottom of the slit 14. This glue can be applied automatically by means of rollers or brushes or in any other suitable manner. After this glue is applied the flap 13 is bent around the upper end of the mouth of the bag and down on the opposite side so that its glued face engages the upper end or mouth of the bag and also the opposite side, as best shown in Fig. 3. After being so bent the mouth of the bag and the flap 13 is passed between rollers so that the flap 13 is securely glued in position and at the same time a part of the glue 17 is forced into the holes 18 thereby filling out the excess of these holes and preventing the powdered materials from entering the same. It will be observed that in this form of the invention not only does the glue 17 completely seal the mouth of the bag and the oversize holes 18 caused by the sewing machine needle in stitching but it also strengthens the stitches 16. In order that these stitches tear loose it is necessary that they be pulled through the walls of the bag and by embedding these stitches in glue and also causing them to adhere to the flap 13 such pulling through of the stitches is entirely prevented in any normal handling of the bags.

In the form of the invention shown in Fig. 5, the outer shell or wall 11 of the bag is extended upwardly on both sides of the mouth 12 and this outer shell or wall 11 is slit at the ends of its mouth in the same manner as the slit 14 in the form of the invention shown in Figs. 1-4. This provides in effect two opposing flaps 21 and 22 which extend upwardly from opposite sides of the bag. In sewing the bag these flaps 21 and 22 are bent downwardly into a horizontal position and the stitching 15 is started at one end of the mouth of the bag and passes through the opposite walls 45 of the inner shell 10 and intermediate shell 10-a. A layer of glue 23 is then applied to the inner or upper faces of the flaps 21 and 22. The flap 22 is then bent over the mouth of the bag and then downwardly so that its glued face engages the 50 mouth of the bag and also the opposite outer side of the intermediate wall or shell 10-a. This flap 22 is then rolled or pressed so that its glue forms a firm bond with the mouth of the bag and also a part of this glue is forced into the oversized holes 55 18 formed during the sewing operation thereby plugging these holes and preventing the escape or loss of any dusty material therethrough. Thereafter the other flap 21 is bent around the outer face of the flap 22 and is rolled down so that its 60 glue 16 forms a firm bond with the flap 22. It is therefore apparent that the mouth of the bag is securely closed by means of the stitching 15 and that at the same time this stitching is reinforced and the mouth of the bag and the stitching sealed 65 against the escape of material by the glued flaps 21 and 22.

In the form of the invention shown in Figs. 6 and 7 one side of the outer wall or shell 11 is extended upwardly to form a flap 13 as in the preferred construction shown in Figs. 1-4 but the bag is unprovided with the slit 14 at opposite ends of the mouth of the bag. In this form the flap 13 remains in an upstanding position during the sewing operation and the stitching 15 extends 75

through all of the walls of the bag and sews its opposite sides firmly together to provide a closure for the mouth of the bag. A layer of glue 19 is then applied to the corresponding face and upper part of the flap 13 and this flap is folded over the mouth of the bag and downwardly so that its glued face engages the opposite side of the bag and also the exposed part of the stitching 15. This flap 13 is then rolled down to secure a good bond between it and the opposite side of the bag and also to cause a part of the glue to be forced into the oversize holes 18 formed by the sewing machine needle in stitching. At the same time a layer of glue 20 is applied to the stitching at the opposite side of the bag, this glue entering the oversize holes 18 from that side of the bag and insuring an adequate and perfect seal of these holes so that the dusty material cannot escape therethrough.

In the form of the invention shown in Fig. 8, the bag is formed with the flap 13 in the same manner as in the form of the invention shown in Figs. 6 and 7. Before sewing the bag, however, a layer of glue 24 is applied along one side of the inner wall 10 of the bag immediately inside its mouth 12. When the bag is put through the sewing machine the sides of the bag are rolled down so that this layer of glue 24 forms a seal for the mouth of the bag. The stitching is started at one end of the mouth of the bag and extends through the opposite sides of the bag so that all of its walls are sewn together. In providing the stitching 15 the holes 18 formed by the sewing machine needle are, of course, larger than the thread 15 and consequently in the absence of provision to prevent it the dusty material would leak out through these holes. To prevent this a layer of glue 25 is applied to the exposed stitches at one side of the bag and forced into the stitching so that a part of the glue enters the holes 18 from that side of the bag and simultaneously another layer of glue 26 is applied to the opposite side of the bag at the stitching so that the glue enters the holes 18 from the opposite side and completes the sealing of the holes. The flap 13 is then folded over the mouth of the bag and down the opposite side thereof and rolled into place so as to form a firm bond with the layer of glue 25. It is also obvious that the layer of glue could be applied to the flap 13 instead of the body of the bag if desired.

In the form of the invention shown in Figs. 9 and 10, the invention is shown as applied to a gusseted bag. In this form the bag composed of the inner shell or wall 10 and the outer shell or wall 11 is provided with an end wall or gusset 27 so that the bag when opened is of rectangular form in a horizontal section.

In this form the mouth of the inner wall or shell 10 is brought together and folded as indicated at 28 so as to provide an interlock. One side wall of the outer shell 11 is extended upwardly to provide a flap 13 similar to the flap 13 shown in the form of the invention illustrated in Figs. 6 and 7 and a layer of glue 29 is applied to the inner side of this flap 13. This flap 13 is then folded down over the top of the bag and the interlock 28 and down against the opposite side of the bag so that it covers the bag and forms a seal which prevents the escape of any of the powdered or dusty material. In this form of the invention sewing or stitching is not employed, although it could be if desired.

It will be noted that the invention has been shown and described as embodied in the sealing

of a bag already fabricated. It is obvious, however, that the invention can be embodied in closing the bottom of the bag as well and that the bag can be closed and sealed at both ends in accordance with the invention and the invention is therefore to be construed as equally applicable to this use.

It is apparent from the foregoing that all of the forms of the present invention provide a bag in which the closure is strong and durable and equal to any other portion of the bag; the bag is sealed so as to be sift-proof at this closure; there is no danger of bits of glue breaking and falling into the contents of the bag so as to contaminate the contents; the seal is neat in appearance and the closing and sealing of the bag can readily be effected by automatic means. It will also be observed that the sealing not only seals the closure so as to prevent the filtering out of the dusty materials which the bag is designed to contain but also strengthens the closure.

Each of the forms of the invention seals the bag so as to prevent contamination thereby permitting its use for foodstuffs and also provides a seal which is pilferproof thereby permitting its use for shipping valuable materials which are particularly subject to pilfering.

While the bag has been shown and described with particular reference to a multiple walled bag it is apparent that some features of the invention can be embodied in a single walled bag and the invention therefore also comprehends this application.

We claim as our invention:

1. A bag comprising a multi-walled tubular body made of flexible material and having a mouth at at least one end and the outer wall at at least one side of said bag being extended to form a flap adapted to embrace the other walls at the mouth of the bag, means for fastening together the opposite sides of said other walls at the mouth of said bag and a hardening plastic material covering all of the exposed parts of said fastening means and sealing the mouth of said bag and at least a part of said hardening plastic material securing said flap over the mouth of said bag.

2. A bag comprising a multi-walled tubular body made of flexible material, and having a mouth at at least one end and the outer wall at at least one side of said bag and adjacent said mouth being extended to form a flap, fastenings extending through opposite sides of the inner wall of said bag at its mouth and forming a closure therefor and a hardening plastic material securing said flap over the mouth of said bag, said hardening plastic material forming a seal for the mouth of said bag and also a seal for the opposite ends of the holes made in said bag by the penetration of said fastenings.

3. A multiple walled bag comprising a multiple walled tubular body made of flexible material and having a mouth at at least one end, the outer wall of said bag projecting outwardly beyond said mouth at at least one side of said bag, fastenings extending through opposite sides of the inner wall of said bag adjacent its mouth and an adhesive for securing said flap over the mouth of said inner wall, said flap covering the exposed parts of said fastenings at at least one side of said bag.

4. A multiple walled bag comprising a multiple walled tubular body made of flexible material and having a mouth at at least one end, the outer

- wall of said bag being slit inwardly from the mouth at diametrically opposite places and said outer wall between said slits and on at least one side being extended outwardly to form a flap,
- 5 fastenings extending through opposite sides of the mouth of an inner wall and forming a closure for said mouth, and a hardening plastic material securing said flap over the mouth of said bag and sealing said closure and also the openings made in said bag by the penetration of said fastenings.
- 10 5. A multiple walled bag, comprising a multiple walled tubular body made of flexible material and having a mouth at at least one side, the outer wall of said bag being slit inwardly from the mouth at diametrically opposite places to points below the mouth of said inner wall and said outer wall between said slits being extended to form two outwardly projecting flaps, fastenings extending through the opposite sides of an inner wall to form a closure for the mouth of said inner wall, a hardening plastic material securing one of said flaps over the mouth of said inner wall and forming a seal for said mouth and also for each end of the holes made in said inner wall by the penetration of said fastenings, and additional hardening plastic material securing the other flap over said first flap.
- 15 6. The method of closing a multi-walled tubular body having a mouth at at least one end and the outer wall at at least one side of said body being extended to form a flap adapted to embrace the other walls at the mouth of the bag which consists in passing fastenings through the opposite sides of said other walls at the mouth of said body and applying a hardening plastic material to all of the exposed parts of the fastenings of said body and folding said flap over the mouth of said body so as to be held in such folded condition by said hardening plastic material.
- 20 7. The method of making a multi-walled bag comprising at least two tubular bodies made of flexible material and having a mouth at at least one end and the wall of the outer tubular body at at least one side of said bag being extended to form a flap, which consists in passing fastenings through opposite sides of the inner body of said bag at its mouth and forming a closure therefor and applying a hardening plastic material to said flap and the mouth of the inner body of said bag thereby to secure said flap over said mouth and form a seal for the openings made in the walls of said bag by the penetration of said fastenings.
- 25 8. The method of making a bag comprising a multiple walled tubular body made of flexible material and having a mouth at at least one end and the outer wall of said bag being slit inwardly from the mouth at diametrically opposite places and said outer wall between said slits and on at least one side being extended outwardly to form a flap, which consists in passing fastenings through opposite sides of the mouth of an inner wall to form a closure for said mouth and applying a hardening plastic material to said flap and securing said flap over the mouth of said bag, said hardening plastic material sealing said closure and also the openings made in said bag by the penetration of said fastenings.
- 30 9. The method of making a bag comprising a multiple walled tubular body made of flexible material and having a mouth at at least one end, the outer wall of said bag being slit inwardly from the mouth at diametrically opposite places to points below the mouth of said inner wall and said outer wall between said slits being extended

to form two outwardly projecting flaps, which consists in passing fastenings through the opposite sides of an inner wall, above said slits to form a closure for the mouth of said inner wall, applying a hardening plastic material to secure one of said flaps over the mouth of said inner wall and forming a seal for said mouth and also for each end of the holes made in said inner wall by the penetration of said fastenings and additional hardening plastic material securing the other flap over said first flap.

10 10. A bag comprising a multi-walled tubular body made of flexible material and having a mouth at at least one end, the outer wall of one side of said bag being extended to form a flap projecting outwardly beyond said mouth and adapted to embrace the other walls at the mouth of the bag, stitching extending through the said other walls of said bag and closing said mouth and an adhesive securing said flap over said mouth and the stitching at at least one side of said bag.

11. A bag comprising a multi-walled tubular body made of flexible material and having a mouth at at least one end, the outer wall of said bag being extended to form a flap projecting outwardly beyond said mouth, stitching uniting the sides of the inner wall of said bag to close its mouth and an adhesive securing said flap over said mouth and securing said flap to the opposite side of the bag.

12. A multiple walled bag comprising a multi-walled tubular body made of flexible material and having a mouth at at least one end, the outer wall of said bag being slit inwardly from the mouth at diametrically opposite places and said outer wall between said slits and on one side being extended outwardly to form a flap, fastenings extending through opposite sides of the mouth of an inner wall and also through the side of said outer wall opposite said flap, said fastenings forming a closure for said mouth, and a hardening plastic material securing said flap over the mouth of said bag and sealing said closure and also the openings made in said bag by the penetration of said fastenings.

13. A bag comprising a tubular body made of flexible material and having a mouth at at least one end and the wall at at least one side of said bag and adjacent said mouth being extended to form a projecting flap, fastenings extending through opposite sides of the wall of said bag at its mouth and forming a closure therefor, a hardening plastic material securing said flap over the mouth of said bag, said hardening plastic material forming a seal for the mouth of said bag and also a seal for the adjacent ends of the holes made in said bag by the penetration of said fastenings and additional hardening plastic material applied to the exposed parts of said fastenings on the opposite side of said bag and forming a seal for the opposite ends of the holes made in said bag by the penetration of said fastenings.

14. The method of making a bag comprising a tubular body made of flexible material and having a mouth at at least one end and the wall at at least one side of said bag being extended to form a flap which consists in passing fastenings through opposite sides of the wall of said bag at its mouth and forming a closure therefor, applying a hardening plastic material to said flap and mouth of said bag thereby to secure said flap over the mouth of said bag and form a seal for said closure and for the adjacent ends of the openings made in said bag by the penetration of

said fastenings and applying additional hardening plastic material to the exposed parts of said fastenings on the opposite side of said bag thereby to form a seal for the opposite ends of the 5 holes made in said bag by the penetration of said fastenings.

15. A bag comprising a multi-walled tubular body made of flexible material and having a mouth at at least one end and the outer wall of 0 one side of said bag being extended to form a flap adapted to embrace the other walls at the 5 mouth of the bag, means for fastening together the opposite sides of the mouth of said bag and a hardening plastic material covering all of the exposed parts of said fastening means and sealing the mouth of said bag and at least a part 10 of said hardening plastic material securing said flap over the mouth of said bag.

16. The method of closing a multi-walled tubular body having a mouth at at least one end and the outer wall of one side of said body being extended to form a flap which consists in passing fastenings through the opposite sides of the mouth of said body and applying a hardening 5 plastic material to all of the exposed parts of the fastenings of said body and folding said flap over the mouth of said body so as to be held in

such folded condition by said hardening plastic material.

17. A bag comprising a tubular body having side walls made of an interior ply of flexible material and having a mouth at one end, an exterior reinforcing ply of flexible material extended adjacent to and parallel with said mouth, stitching extending through said plies and closing said mouth, a sealing flap folded over the mouth of 10 said bag and embracing the stitching on both sides and an adhesive securing said sealing flap in place.

18. As an article of manufacture, a bag composed of a tubular body made of plies of flexible material and having a mouth at one end, and 15 means for fastening together opposite side plies of said bag to provide a closure, said fastening means comprising a line of stitches and an adhesive, at least one side ply of the bag material 20 being formed with a freely extending flap adapted to be folded over to enclose underlying ends of the plies of bag material and said fastening means at both sides and to be secured adhesively thereto.
